CLAIM

The ornamental design for a broom block, as shown and described.

DESCRIPTION

FIG. 1 is a top right front perspective view of a broom block showing our new design;

FIG. 2 is a top plan view thereof;

FIG. 3 is a bottom plan view thereof;

FIG. 4 is a front elevational view thereof; the rear elevational view being a mirror image; and,

FIG. 5 is a right side elevational view thereof; the left side elevational view being a mirror image.

The broken lines that are shown in FIG. 1 are for illustrative purposes only and form no part of the claimed design.
